ENGRAVING MACHINE

Ernest Albert Cooke, Leicester, England, assignor
to Kapella Limited, Leicester, England, a company of Great Britain

Application October 25, 1939, Serial No. 301,292
In Great Britain October 20, 1938

8 Claims. (Cl. 90—62)

This invention relates to engraving machines of the kind in which the desired engraving, comprising lettering or other impressions which can be built up from standard elements arranged in ordered sequence, is obtained by scale reproduction from "copy" arranged in a copyholder. Hitherto "copy" has usually comprised small thin metal plates, each embodying a letter or other character and having two bevelled edges engaging in a dovetailed groove in the copyholder. Such an arrangement involves not only the use of relatively expensive material, such as steel or brass, for the copy in order to provide adequate strength and durability in thin strips, but also relatively high manufacturing costs owing to the necessity of milling the bevels on the copy and the dovetailed groove or grooves in the copyholder.

An object of the present invention is to provide an improved copyholder comprising a pair of parallel guides one of which is plane and oblique to the operative surface of the copy whilst the second may also be a plane surface or may be convexly curved or otherwise shaped in section to give line contact with the copy elements.

In the accompanying drawings

Figures 1 and 2 show one example of copy holder according to the invention in plan and side elevation respectively,

Figure 3 is a section on the line V—V of Figure 1,

Figure 4 illustrates in plan a modified form of copyholder,

Figure 5 is a section on the line V—V of Figure 4,

Figures 6, 7 and 8 show respectively three further arrangements of the guide surfaces for the copy elements, and

Figures 9 and 10 illustrate two preferred forms of copy element.

In the construction shown in Figures 1 and 2 the copyholder consists of a horizontal framework G carried by means of a socket member G¹ engaging a vertical rod G² to which it can be clamped, by a grub screw G³, in any desired rotational position, the rod G² being clamped in any desired position of adjustment on the engraving machine indicated generally at G⁴. To this end the rod G² is locked in the desired longitudinal position of adjustment in a carrier G⁵ by means of a grub screw G⁶, the carrier G⁵ being in turn locked in the desired position of adjustment along a guide G⁷ by a ball handle G⁸. The horizontal framework G comprises horizontal bars H rigidly held together by cross-connections H¹, H², the

cross-connections H² carrying the socket member G¹. There are thus formed between the bars H channels H³ for the reception of copy elements F¹ of right-angled triangular section. Within each channel H³ and to one side thereof a guide rod J of circular section extends from end to end, each rod J being secured to the framework G by studs J¹ so that the rod lies in one corner of the corresponding channel H³ and provides an unobstructed cylindrical guide surface for the copy elements. The opposite face H⁴ of the channel is machined to provide a vertical plane guide surface of sufficient height to constitute an abutment for one of the equal faces F, F¹ of the copy element. The spacing between each rod J and the associated plane guide surface H⁴, which are made accurately parallel to one another, is chosen to suit the size of the copy elements so that these can be dropped into the channel H³ and will rest therein each with its hypotenuse face bearing on the rod J and making a line contact therewith, and its face F lying flat against the corresponding guide surface H⁴. The remaining faces F¹ of the copy elements will thus lie horizontally in proper alignment with one another and just above the top surface of the framework G as clearly shown in Figures 2 and 3. The copy elements are held against longitudinal displacement by means of end clamps J² on the rods, spacers (not shown) being inserted between the copy elements if desired.

In the modified arrangement shown in Figures 4 and 5 the copy holder is adapted to support copy elements of equilateral triangular section, that is to say having three equal faces F², F³, F⁴. The framework G is provided with two channels F⁵ each having two machined plane guide surfaces F⁶, F⁷, inclined to each other in accordance with the angle of the copy element. The elements are held against longitudinal displacement by end blocks L each of which fits into the slot formed between the guide surfaces F⁶, F⁷ and has a slightly convex surface for engaging the adjacent copy element, as clearly shown in Figure 4. Each block L has a central aperture through which freely extends the screwed spindle of a knurled locking head L¹, the said spindle engaging a corresponding threaded hole in a squared nut L² lying within a widened passage L³ extending along the bottom of the slot F⁵. Thus, by releasing the locking heads L¹ the blocks L can be longitudinally adjusted along the slots F⁵ and relocked in the position of adjustment.

It will be appreciated that the above arrangements may be modified in various ways. For ex-

ample, with a copy element of right-angled triangular section, the second guide surface may be constituted by a convex surface, for example as shown at K in Figure 6 to give line contact with the hypotenuse face of each copy element. In Figure 7 the guide K¹ is constituted by the edge between two surfaces K², K³, the surface K² being parallel to the guide surface H⁴ whilst the surface K³ is horizontal and lies at a level somewhat below the top surface of the framework G. In Figure 8, the first guide surface H⁵ is inclined to the horizontal whilst the second guide is provided by the angle H⁶ formed in the framework so as to give line contact with the cooperating faces of the copy elements. The use of an equilateral triangular section has the advantages of being somewhat less susceptible to accidental displacement and of affording three faces for bearing characters.

The copy elements may be made of metal or of other material such as synthetic resin, or partly of metal and partly of such other material. They may be manufactured in a variety of ways. Thus, for example, blanks for the elements may be produced by cutting appropriate lengths from extruded rod or tube of the desired triangular section, such blanks having formed on them, for example by engraving or stamping, the appropriate character or characters. In the case of elements of right-angled isosceles section, one example of which is shown in Figure 9, the two equal faces F, F¹ may bear identical characters or similar characters of different size, or different characters, for example the same letter in capital and in lower case. In Figure 10 each copy element has an equilateral triangular section which affords three faces F², F³ and F⁴ for bearing characters.

Instead of forming the copy elements by cutting appropriate lengths from a rod or tube of the desired triangular section the elements may be made, individually or in the form of rods or tubes for subsequent cutting, by pressing or casting or moulding or rolling, and in this case it will often be convenient to impress the character or characters on the elements during the manufacturing process. The method of manufacture will be chosen to suit the material used. It may be convenient in some instances to embody each character on a small thin plate, for example of metal, such plate then being incorporated by a moulding process in a block of, say, synthetic resin of the appropriate sectional shape.

It will be appreciated that by such methods of manufacture it is possible to produce copy economically in large quantities in a form which will not only be convenient to use but will also be robust enough to withstand the stresses of handling and of use in the machine.

What I claim as my invention and desire to secure by Letters Patent is:

1. A copyholder for an engraving machine, comprising a support carrying two laterally spaced guides upon and between which the copy rests, one of said guides having a plane supporting surface which makes plane surface contact with the copy whilst the second guide has a curved supporting surface which makes line contact with the copy.
2. A copy-holder as claimed in claim 1, in which the second guide is constituted by a cylindrical part mounted on the support.
3. A copyholder as claimed in claim 1, in which the second guide is constituted by a convexly curved part of the support.
4. For use in engraving machines, a copy assembly comprising, in combination, a support carrying two laterally spaced guides, and at least one copy element of triangular cross-section resting upon and between the guides which respectively make plane surface contact with two faces of the copy element.
5. For use in engraving machines, a copy assembly comprising, in combination, a support carrying two laterally spaced guides, and at least one copy element of triangular section resting upon and between the guides, one of which makes a plane surface contact with one face of the copy element whilst the second guide makes a line contact with another face of the copy element.
6. For use in engraving machines, a copy assembly comprising, in combination, a support carrying two guides in fixed lateral spaced relationship, at least one of the guides being constituted by a plane surface, and at least one copy element freely resting upon and between the guides and having a plane surface engaging with the plane guide surface and inclined to the operative surface of the element.
7. A copyholder for an engraving machine, comprising a support carrying two laterally spaced guides, upon and between which the copy rests, the two guides being constituted respectively by two plane surfaces inclined to one another and to the operative surface of the copy.
8. A copy assembly for use in engraving machines, comprising, in combination, a support carrying two guides in fixed lateral spaced relationship, and at least one copy element freely resting upon and between the guides, one of the guides and the copy element engaging with one another at at least three non-collinear points in a plane inclined to the operative surface of the copy element, whilst the other guide and the copy element engage with one another at at least one point.

ERNEST ALBERT COOKE.
